DUPLICATING MECHANISM

Harold G. Johnstone, Chicago, Ill., assignor to
Western Electric Company, Incorporated, New
York, N. Y., a corporation of New York

Application May 13, 1932, Serial No. 611,031

9 Claims. (Cl. 164—114)

This invention relates to duplicating mechanisms, and more particularly to pneumatically controlled mechanisms for duplicating statistical record cards.

5 It is an object of the present invention to provide a simple mechanism for rapidly duplicating records.

In accordance with one embodiment, the invention contemplates the provision of a mechanism for perforating duplicates of a supply of record cards having various indicia therein, wherein tabulating cards to be duplicated are advanced under and engaged by a head connected to a source of compressed air and having cooperating therewith a block having a plurality of pistons therein, one for each possible perforation in the record card to be duplicated. After a card is moved into position beneath the head, air under pressure is supplied to the head and forced through the apertures in the card to be duplicated, to force downwardly the pistons associated with those particular perforations. The pistons upon being forced downwardly will be locked in their downward position and will serve as abutments against which perforating pins may be lifted by a blank card supported on a die plate, so that those pistons which are locked in their downward position will cause their corresponding perforating pins to pass through the record card while those perforating pins associated with pistons not locked in their downward position will be lifted by the record card without perforating the card.

Mechanism is also provided for advancing the cards to the perforator pins and to the pneumatic head in predetermined timed relation so that a card which has been perforated will be advanced from under the perforating pins during that portion of the machine cycle wherein a new card to be duplicated is controlling the setting up of the pistons.

These and other objects of the invention will be apparent from the following detailed description, when considered in connection with the accompanying drawings, wherein:

Fig. 1 is a side elevational view of a record card duplicating apparatus embodying the novel features of the invention;

50 Fig. 2 is an enlarged fragmentary vertical sectional view taken along the line 2—2 of Fig. 1 in the direction of the arrows, parts being broken away to show more clearly the details of construction;

55 Fig. 3 is a fragmentary vertical sectional view

taken along the line 3—3 of Fig. 2 in the direction of the arrows;

Figs. 4 and 5 are fragmentary horizontal sectional views taken along the lines 4—4 and 5—5 respectively of Fig. 3 in the direction of the arrows;

Figs. 6 and 7 are fragmentary vertical sectional views taken along the lines 6—6 and 7—7 respectively of Fig. 3 in the direction of the arrows, and

Fig. 8 is a fragmentary vertical sectional view taken along the line 8—8 of Fig. 7 in the direction of the arrows.

Referring now to the drawings wherein like reference numerals designate like parts throughout the several views, power for driving the various movable parts of the mechanism is supplied from a motor (not shown) through a belt 10 (Figs. 2, 6 and 7) which drives a pulley 11 fixed to a sleeve 12. The sleeve 12 is freely 20 rotatable upon a shaft 13, mounted in a manner to be described hereinafter. The sleeve 12 is held against lateral movement on the shaft 13 by collars 14 and 15 pinned to the shaft, and has formed integrally therewith a worm gear 16 which meshes with a worm gear 17 fixed to one end of a shaft 18 (Figs. 1, 6 and 7). Mounted upon the other end of the shaft 18 is a worm gear 19 (Fig. 1) which meshes with a worm gear 20 fixed to a stud shaft 21 carrying a bevel gear 22. Meshing with the bevel gear 22 is a bevel gear 32 mounted on one end of a shaft 33 which carries intermediate its ends a bevel gear 34 for driving a bevel gear 35 pinned to a shaft 36. The shaft 36 carries bevel gears 37, 38, 39 and 40 which mesh with bevel gears 41, 42, 43 and 44 mounted on shafts 45, 46, 47 and 48.

The shafts 45, 46, 47 and 48 extend transversely through the machine and are journaled in side plates 49 mounted upon a base 50 and have card feed rollers 60 (Figs. 2 and 3) formed integrally therewith for advancing a card to be perforated from a magazine 61 to a receptacle 59 (Fig. 1). Cooperating with the card feed rollers 60 of the shafts 45, 46, 47 and 48 are a plurality of spring pressed upper card feed rollers 62 and 63 (Figs. 1, 2 and 3) which are not positively driven and which are normally urged downwardly into contact with the card feed rollers 60. The upper card feed rollers 62 and 63 are of a known type and a detailed description thereof is not believed to be necessary.

Pinned to the upper end of the shaft 33 (Fig. 1) is a beveled gear 64 meshing with a beveled gear 55

65 secured to a shaft 66 suitably journaled on one of the side plates 49 and carrying beveled gears 67, 68, 69 and 70. Meshing with the beveled gears 67, 68, 69 and 70 are beveled gears 71, 72, 73 and 74, respectively, mounted upon shafts 75, 76, 77 and 78, respectively. The shafts 75 and 78 are journaled in the side plates 49 and extend through the entire machine, whereas the shafts 76 and 77 are stud shafts and extend only a short 10 distance beyond the inner side of one of the side plates 49 (Fig. 1). Carried by the shafts 75 and 78 are a plurality of enlarged card engaging portions 90 similar to the card feed rollers 60 of the shafts 45 and 48 for engaging a card to be duplicated 15 cated. The shafts 76 and 77 carry adjacent the inner sides of the side plate 49, card feed rollers 91 for cooperating with the enlarged portions 90 of the shafts 75 and 78 to advance a card to be duplicated 20 through the machine from a magazine 92 to a receptacle 93 (Fig. 1). The shaft 78 carries at its right end (Fig. 2) a beveled gear 94 which meshes with a beveled gear 95 mounted upon a shaft 96 extending along the right hand side plate 49 (Fig. 2) for driving stud shafts 25 similar to the stud shafts 76 and 77 on the right hand side of the machine (Fig. 2). Cooperating with the card engaging portions 90 and 91 of the shafts 75, 76, 77 and 78, are a plurality of spring pressed upper card feed rollers 97 and 98 similar to the 30 card feed rollers 62 and 63, respectively, and serving the same purpose as the card feed rollers 63.

After the motor is started the card feed rollers will be driven continuously and will tend to advance cards fed thereto from the magazines 61 35 and 92 to their respective receptacles 59 and 93.

The magazine 61 which is adapted to receive a supply of blank cards 99 to be perforated as duplicates of a supply of perforated cards 100 in the magazine 92, is provided with a card feeding finger 101 slidably mounted in the bottom thereof. Extending downwardly from the base of the card feeding finger 101 is a lug 102 having pivoted thereto one end of a link 103 the other end of which is pivoted to a bell crank 104 pivoted on a 45 shaft 105. The bell crank 104 has mounted upon one end thereof a cam roller 106 which extends into a cam groove 107 in a cam 108 (Fig. 1).

A card feeding finger 109 (Fig. 1) is slidably mounted on the bottom of the magazine 92 and 50 is provided with downwardly and outwardly extending lugs 110 which extend through slots 115 in the side plates 49 and are interconnected with the upper ends of a bifurcated bell crank 111 by links 112. The bell crank 111 is pinned at 113 to the shaft 105 and has a cam roller 114 mounted in a cam groove 116 of cam 108. The card feed fingers 101 and 109 have card engaging portions 116 and 117, respectively, for engaging the bottom cards in their respective magazines to advance them through card slots 123 and 129, respectively, and into engagement with the card feed rollers driven by the shafts 48 and 78, respectively. Due to the fact that the cam rollers 106 and 114 are actuated by the same cam at different times in each cycle of rotation of the cam, in the direction of the arrow (Fig. 1), a card from the supply of cards 100 will be advanced to its associated card feed rollers at a predetermined time in the cycle of rotation of the cam and 65 shortly thereafter a card from the supply of cards 99 will be advanced to its associated card feed rollers to advance the cards through the machine in echelon formation; that is, the card from the supply 100 will be slightly in advance of the card 70 75 from the supply 99.

The cam 108 is mounted upon a shaft 130 journaled in brackets 117 suspended from the base 50 and has secured thereto a gear 131 adapted to be driven by a train of gears indicated generally at 132 which in turn are driven by a gear 133 (Figs. 1 and 7) mounted upon the shaft 13 and adapted to be rotated thereby.

The shaft 13 is journaled in the side plates 49 and has pinned thereto a driven clutch member 134 (Figs. 2, 6 and 7). Cooperating with the driven clutch member 134 is a driving clutch member 135 which is slidable longitudinally of the shaft 13 and which is provided with horizontally extending arms 136 which are slidable in apertures 137 in the pulley 11. The driving clutch member 135 rotates with the pulley 11 and is provided with a circumferentially extending groove 138 into which extend arms of a bifurcated lever 139 (Figs. 3, 6 and 7) pinned to a shaft 140 journaled upon the base 50 and normally urged to rotate in a counterclockwise direction (Figs. 6 and 7) by a coil spring 141 (Fig. 3) thereby to hold the driving clutch member 135 out of engagement with the driven clutch member 134. Also pinned to the shaft 140 is a vertically extending control lever 153 (Figs. 2, 3 and 7) which will normally be held in the position shown in Figs. 2 and 7 by the spring 141, but which may be moved to the right (Figs. 2 and 7) to rock the shaft 140 in a clockwise direction and through the bifurcated lever 139 move the driving clutch member 135 into engagement with the driven clutch member 134. The lever 153 has cooperating therewith a flexible rod commonly known as a "Bowden" wire 154 for moving it to the right (Fig. 7). The "Bowden" wire 154 is enclosed in a casing 155 secured to a bracket 156 mounted upon the base 50 and the "Bowden" wire may be operated by a suitable push button of any known type conveniently mounted for operation by an operator. The lever 153 upon being moved to the right (Fig. 7) will engage a latch member 157 pivoted to the side plate 49 at 160 and normally urged about its pivot in a counterclockwise direction and into engagement with a stop member 159 by a spring 45 158 to a position where it will lock the driving clutch member 135 in engagement with the driven clutch member 134 due to the engagement of the end of the lever 153 with a stop 161 formed on the latch 157, thereby to cause the shaft 13 to rotate continuously until the latch 157 is released from the lever 153. A second "Bowden" wire mechanism indicated generally at 162 (Figs. 2, 3 and 7) and mounted upon the bracket 156 55 may be actuated to move the latch member 157 upwardly out of engagement with the lever 153 thereby to permit the spring 141 to return the lever 153 to its normal position as shown in Figs. 2 and 7 for moving the driving clutch member 135 out of engagement with the driven clutch member 134.

After a card has been withdrawn from the bottom of the magazine 92 the card feed rollers 90 and 91 tend to advance it through the machine and into the receptacle 93. However, the card in transit from the magazine 92 to the receptacle 93 will be engaged by a card stop 163 (Figs. 2 and 3) which will be interposed in the path of the card. The card stop 163 is attached to a pneumatic head 164 which is reciprocably mounted in the side plates 49 and which is adapted to be reciprocated by a pair of cams 165 mounted upon the shaft 13 and provided with cam grooves 166 in which travel cam rollers 167 mounted upon the lower ends of levers 168 and having their 70 75

other ends secured to the pneumatic head 164 at 169.

When a card is stopped under the pneumatic head 164 by the card stop 163, the head 164 will 5 continue its downward movement to clamp the card under it and shortly after the card is clamped by the head a camming pin 180 (Fig. 1) mounted upon one of the cams 165 will engage with and move a valve operating lever 181 in a 10 counterclockwise direction (Fig. 1) to open a valve 182 and permit air under pressure from a source (not shown) to pass from a pipe 183 into a pipe 184 which is interconnected with the pneumatic head 164 by a pipe 185 and a flexible 15 connection 186. A blast of air under pressure will thus be delivered through a port 187 (Fig. 3) formed in the pneumatic head 164 and into the interior of the head. The upper surface of the pneumatic head is rounded and extends down- 20 wardly to a grid 188 which is sealed thereto and which is provided with 45 columns of apertures 189, there being 12 apertures in each column. These apertures 189 are so positioned as to be in direct vertical alignment with every possible hole 25 position of a statistical card advanced from the supply of cards 100 when the card is stopped under the pneumatic head 164 by the card stop 163, the blast of air directed from the pipe 183 upon the opening of the valve 182 will be directed 30 through the grid and through all of the holes in a card, a duplicate of which is to be made.

As the shaft 13 continues to rotate the camming pin 180 will engage an upwardly extending arm 190 (Fig. 1) of a reciprocable lever 191 slid- 35 ably mounted upon the base 50 by means of a bracket 194 and having an arm 192 thereof engaging a downwardly extending portion 193 of the valve operating lever 181. When the camming pin 180 engages the arm 190 of the lever 191 it will move the lever 191 to the left (Fig. 1) thereby to rock the valve operating lever 181 in a clockwise direction (Fig. 1) to close the valve 182 and shut off the supply of air under pressure from the pipe 184.

In direct vertical alignment with the apertures 189 in the grid 188 (Figs. 2 and 3) are a plurality of cylinders 204 formed in a cylinder block 205 secured to the side plates 49 and slidably mounted in each cylinder is a piston 206 which 50 has associated with it a coiled spring 207 for normally urging it upwardly. The coiled spring 207 for each piston 206 surrounds a reduced portion 208 of the piston and resiliently engages a shoulder 209 of the piston and the upper surface 55 of a guide plate 210 mounted between the side plates 49.

The lower portion of each of the pistons 206 is slidable in an aperture 211, individual thereto and formed in the guide plate 210 and is provided 60 with a notch 212, so that when a piston is moved downwardly it will be locked in its downward position due to the engagement of the notch 212 with a spring pressed latch plate 213 provided 65 with a plurality of apertures 214 corresponding in number to the number of pistons in a column. There is provided one latch plate 213 for each column of pistons and these plates are normally urged to the left (Fig. 3) by contractile springs 70 215 which normally tend to move the latch plates into engagement with a stop member 216 ex- 75 tends transversely to the direction of movement of the latch plates 213 and secured to the guide plate 210. The stop member 216 prevents movement of the latch plates 213 to the left

(Fig. 3) beyond a predetermined point where a tapered edge 217 formed on each of the pistons may engage one edge of its associated aperture 214 to cam the latch plate to the right (Fig. 3) until the plate engages in one or more of the notches 212 in its associated column depending on the number of pistons depressed in a particular column. If it is desired to leave imperforate any column of a duplicate statistical record card despite the fact that the record card being 10 duplicated has perforations in that particular column, the latch plate 213 for that column may be latched in its right hand position (Fig. 3) by means of manually settable stops 218 of which there is provided one for each latch plate. The 15 stops 218 when inoperative are in the position shown in full lines in Fig. 3 and may be moved manually to their operative position as shown in dotted lines.

The pistons 206, upon being actuated to move 20 downwardly, will be latched in their downward position by the latch plates 213 except those in columns it is desired to avoid for a predetermined portion of the cycle of rotation of the shaft 13 to control perforating pins 230 (Figs. 2 and 3) 25 of which there is provided one for each possible card hole in a statistical record card having 45 columns with 12 possible holes in each column. After the pistons 206 have controlled the operation of the perforating pins 230, as described 30 hereinafter, the pistons will all be released simultaneously to permit their associated springs 207 to move them to their upper position as shown in Figs. 2 and 3 due to the movement of all the latch plates 213 to the right (Fig. 3) except those 35 previously locked in their releasing positions, by a release bar 231 common to all of the plates 213 engaging release pins 232 fixed to each of the latch plates. The release bar 231 (Figs. 1, 3 and 4) is fixed to the end of a pair of levers 233 40 pinned to a shaft 234 journaled in the side plates 49 and having pinned thereto a lever 235 (Fig. 8). The lever 235 carries at its lower end (Fig. 8) a cam roller 236 which rides in a cam groove 237 45 formed in a cam 238 fixed to the shaft 13 so that once in each revolution of the shaft 13 the shaft 234 will be oscillated to move all of the latch plates 213 except those avoided to the right (Fig. 3) to release their associated pistons 206. 50

The perforating pins 230 are each provided with a head 239, the lower edges of which rest upon a guide plate 240 for normally supporting the pins 230 in the position shown in Figs. 2 and 3. The guide plate 240 has a plurality of apertures 241 in which the pins 230 are slidable 55 and is supported between the side plates 49.

A guide plate and die unit indicated generally by the numeral 250 is reciprocably mounted in the side plates 49 at 251 and comprises upper and lower guide plates 252 and 253, respectively, and a die plate 254 provided with apertures 255, 256 and 257, respectively, in which the perforating pins 230 may move and the guide plate 253 is spaced from the die plate 254 to permit 60 the passage of a record card therebetween, suitable slots being formed in all the plates to receive the card feed rollers 60 and 63.

A card which has been advanced from the magazine 61 to a position upon the die plate 254 70 will be stopped thereon by a card stop 258 (Figs. 2, 3, 7 and 8) mounted upon the end of a lever 259, the other end of which is pivoted on the shaft 234 (Fig. 8). Intermediate the ends of the lever 259 there is formed a downwardly extend- 75

ing portion 260 (Fig. 8) which carries a cam roller 261 mounted in a cam groove 262 of a cam 263 fixed to the shaft 13. The cam 263 will move the card stop 258 into the path of a card advanced from the magazine 61 to position the card under the perforating pins 230 and upon the die plate 254 for a short interval while the card is perforated. This short interval occurs immediately after the pistons 230 have been 10 locked in their downward position.

While a card is held upon the die plate 254 by the card stop 258, the guide plate and die unit 250 will be reciprocated by a pair of actuating levers 264 secured thereto and having mounted 15 upon their lower ends cam rollers 265 which extend into cam grooves 266 formed in cams 267 mounted on the shaft 13 (Figs. 2, 3 and 7). Each time the cams 267 move the guide plate and die unit 250 upwardly a card positioned on the die 20 plate 254 will raise all the perforating pins 230 with it, except those pins which encounter the lower ends of pistons 206 which have been moved downwardly due to a blast of air being directed through the apertures in a card to be duplicated 25 and striking the upper surface of the pistons. The pistons 206 which have been driven downwardly will be locked in their downward position and will cause their associated perforating pins 230 to perforate the card positioned upon the 30 die plate 254 with a duplicate of the information contained in the last card to be engaged by the pneumatic head 164.

A better understanding of the invention will be had from the following brief description of 35 the operation thereof.

Assume that a supply 100 of statistical record cards having information punched therein are positioned in the magazine 92 and a supply of blank statistical record cards 99 are positioned 40 in the magazine 61, and assume that it is desired to perforate a duplicate of each of the cards in the magazine 92. The motor (not shown) may be started to drive the pulley 10 thereby to drive all of the card feed rollers 69, 90 and 91 continuously, and to rotate the driving clutch member 135, whereupon the feeding of cards from the magazines 61 and 92 may be started by actuating the "Bowden" wire 154 to move the lever 153 to the right (Fig. 2) and connect the driving 45 clutch member 135 to the driven clutch member 134. In rotating, the clutch member 134 will carry with it the shaft 13, which drives all of the moving parts of the mechanism through their 50 cycles of operation. Early in the cycle of rotation of the shaft 13, the gear 133 will drive the train of gears 132 to cause the cam 108 to rock the lever 111 to the position shown in Fig. 1, thereby to engage the lowermost card of the supply 100 and advance it to the card feed rollers 90 55 and 97 which will in turn drive the card under the pneumatic head 164 which, as the card begins to move thereunder, is moved downwardly due to the downward movement of its levers 168 by the cams 165. The head 164, in moving 60 downwardly, will move with it the card stop 163 so that a card advanced from the supply 100 will be stopped under the pneumatic head for a short time, and while held in that position the camming pin 180 will strike the valve operating 65 lever 181 to permit a blast of air from the source (not shown) to be directed into the pneumatic head 164 and through any holes in the card positioned under the head for driving downwardly 70 those pistons 206 associated with the perfora-

tions in the card held under the pneumatic head 164.

The pistons 206, in moving downwardly, will cam their associated latch plates 213 to the right (Fig. 3) against the tension of the springs 215 5 until the plates 213 engage in the notches 212 formed in the lower ends of the pistons to lock the pistons in their downward position. Any piston in a column the latch plate 213 of which is locked in its right hand position by the manually settable stops 218, will not be locked in its downward position but will be returned to the position shown in Figs. 2 and 3 by the springs 207, as soon as the air under pressure is disconnected from the pneumatic head 164 and the air 15 under pressure is shut off from the pneumatic head 164 shortly after the valve 182 is opened due to the closing of the valve 182 by the moving of the valve operating lever clockwise (Fig. 1) by the reciprocable lever 191. Just after the 20 air under pressure is disconnected from the pneumatic head 164 the head will start to move upwardly and will release the card held under it due to the removal of the card stop 163 from the 25 path of the card and the card feed rollers 98, 97, 90 and 91 will advance the card to its hopper 93.

At approximately the same time that the head 164 begins to move upwardly, the card feeding finger 101 will be moved to the right by the cam 108 to feed a card from the supply 99 of blank 30 cards into position upon a die plate 254, and as the card from the supply 99 moves into position upon the die plate, the card stop 258 will be moved upwardly into the path of the card and will stop it in position between the die plate 254 35 and the guide plate 253, and will hold the card in that position while the guide plate and die unit 250 is reciprocated by the cams 267 driving the levers 264 upwardly out of the position shown in Figs. 2 and 3 and subsequently back to that 40 position. The guide plate and die unit 250, in moving upwardly, will cause the card positioned upon the die plate 254, to engage with all of the perforating pins 230 to carry the pins upwardly with the unit 250, thereby lifting the heads of the 45 pins 239 off of the guide plate 240. All of those perforating pins 230 whose associated pistons 206 have not been locked in their downward position by the latch plates 213, will move upwardly with the card, but those perforating pins 230 50 whose associated pistons 206 have been locked in their downward position, will be held against upward movement and will, in cooperation with the die plate 254, perforate holes in the record card positioned on the die plate in those hole positions corresponding to the hole positions perforated in the record card which just passed out from under the pneumatic head 164. Shortly 55 after the guide plate and die unit 250 returns to its normal position as shown in Figs. 2 and 3, the card stop 258 will be cammed out of the path of the card on the die plate 254, and the card feed rollers 60 will be permitted to advance the card into its receptacle 59.

Continued rotation of the shaft 13 will advance 65 cards one at a time from the magazines 61 and 92 and will perforate the cards from the supply 99 as duplicates of those cards in the supply 100, each rotation of the shaft 13 causing the perforation of a duplicate card. It will be apparent 70 from the description of operation thus far, that the cards from the supply 100 are advanced to the pneumatic head prior to the advancement of a card from the supply 99 to the guide plate and die unit 250, thereby reducing appreciably 75

the length of time required to perforate duplicates of the supply of cards 100.

The shaft 13 will continue to rotate and will feed cards from the magazines 92 and 68 continuously until the motor (not shown) is stopped, or the driving and driven clutch members 135 and 134, respectively, are disengaged due to the actuation of the "Bowden" wire mechanism 162, to move the latch 157 out of engagement with the lever 153, thereby to permit the spring 141 to rock the lever 153 in a counterclockwise direction (Figs. 2 and 7).

Although this invention has been described as relating to a specific card duplicating apparatus, it is to be understood that the invention has many other applications and should be limited only by the scope of the appended claims.

What is claimed is:

1. In a card duplicating apparatus, a reciprocable pneumatic head, a grid secured to the bottom of said head and having apertures therein in alignment with all potential hole positions in a card to be duplicated, means for advancing a card to be duplicated to position under said head, means for lowering said head into engagement with said card to prevent the escape of air between the head and card, means for supplying air under pressure to said head, means controlled by the air passing through apertures in the card to be duplicated for setting up perforators to perforate a duplicate of said card, and means operable in timed relation to the operation of the pneumatic head, for causing the perforators to perforate the duplicate card.

2. In a perforating apparatus, a pneumatic head having a plurality of apertures therein for directing air under pressure through apertures representing information in a record member, said apertures in the head being in alignment with all potential hole positions in the record member to direct the air under pressure through holes in the card and the head engaging the card around each aperture to prevent air from getting under the card, means controlled by the air under pressure passing through the record for producing a duplicate of said information on a second record member, and means operable in timed relation to the operation of said duplicate producing means for moving said pneumatic head into engagement with said first mentioned record member to form an air tight seal between said member and the head.

3. A perforating apparatus comprising means for directing air under pressure through apertures representing information in a record member to take information from the record member including a reciprocable pneumatic head for engaging the record member to apply air under pressure to a surface thereof at spaced positions in alignment with each potential hole position in the record member, means for moving said pneumatic head into firm contact with the surface of the record member to prevent leakage of air between the surface of the member engaged by the head, and means responsive to the air directed through the record member and operable in timed relation to the operation of the pneumatic head for perforating a duplicate of said information in a second record member.

4. A card duplicating apparatus comprising a pneumatic head for directing air under pressure through apertures in a card to be duplicated, a grid secured to the bottom of said head and having apertures therethrough for every possible hole in the card to be duplicated, a block positioned

beneath said head and having cylindrical openings in alignment with the apertures in said grid, means for moving a card into position between said block and said head, means for moving the head into engagement with the card to be duplicated to form an air tight seal between the card and the head, a card stop carried by said head to position a card accurately under said head, spring pressed pistons normally urged toward the head and positioned in the cylindrical apertures in the block, latch portions formed on the lower ends of said pistons, latch plates cooperating with the lower end of said pistons to lock the pistons in operated position, each of said latch plates being adapted to control a plurality of pistons, means for locking said latch plate in inoperative position to prevent the locking of its associated pistons upon their operation by the air passing through a card, a plurality of perforating pins in alignment with said pistons, a die plate cooperating with said pins and adapted to move a second card into engagement with said pins whereby all of said pins will be moved except those associated with pistons locked in their operated position by said latch plates to perforate the information in those portions of the first mentioned record card associated with latch plates not locked in their inoperative position and means for reciprocating said die plate in timed relation to the operation of said pneumatic head.

5. In an apparatus for duplicating record sheets, sensing means including a pneumatic head for directing air under pressure through perforations in a record sheet to be duplicated, a plurality of settable means actuatable by the air under pressure in passing through the record to be duplicated for storing the information sensed, means controlled by said settable means for causing the sensed information to be perforated in a second record sheet, means for advancing sheets to be duplicated to the sensing means, and means for advancing sheets to be perforated to the perforating means while the settable means are being actuated.

6. In a perforating apparatus, sensing means operable in response to apertures in a record card, perforating means for a duplicate record card, means for advancing and stopping a card under the sensing means, means for advancing and stopping a card under the perforating means, and means for causing said cards to be stopped in successive timed relation whereby one card may be perforated while another is being advanced to the sensing means.

7. In a card duplicating apparatus, means for sensing master record cards, settable members controlled by the sensing means for storing information received from the master card, selecting means independent of the master card for selectively determining which of the settable members shall be effective to store information, and means controlled by the effective settable members for perforating a duplicate card after the sensed master card has been removed from the sensing means.

8. In a card duplicating apparatus, sensing means operable in response to apertures in master record cards, means for storing information received from the sensing means, perforating means controlled by the storing means for making duplicate record cards, and means for advancing a new master card under the sensing means while the perforating means is perforating a duplicate card in accordance with information stored from a previously sensed master

card and for advancing a card to the perforating means after a master card has been positioned under the sensing means.

9. In a card duplicating apparatus, a pneumatic head movable into engagement with a card, a grid secured to said head and having apertures therethrough for every possible hole in the card to be duplicated, a block positioned beneath said head and having openings in alignment with the

apertures in the grid, perforating means in operative association with the openings in the block, means for positioning a master card to be duplicated between said block and the grid on said head, and means for admitting air under pressure into the pneumatic head to effect control of the perforating means to perforate a duplicate card in accordance with the master card. 5
